UNITED STATES PATENT OFFICE

112,195

DESIGN FOR A COMBINED HANDLE AND STANDARD FOR A SADIRON OR SIMILAR ARTICLE

Russell I. Huffman, Dover, Ohio, assignor to Knapp-Monarch Company, St. Louis, Mo., a corporation of Missouri

Application March 28, 1938, Serial No. 76,131

Term of patent 3½ years

To all whom it may concern:

Be it known that I, Russell I. Huffman, a citizen of the United States and a resident of Dover, in the county of Tuscarawas and State of Ohio,
have invented a new, original, and ornamental Design for a Combined Handle and Standard for a Sadiron or Similar Article, of which the following is a specification, reference being had to the accompanying drawing, forming part thereof.

Figure 1 is a side elevational view of a combined

handle and standard for a sadiron or similar article showing my new design.

Figure 2 is a front elevational view of the handle; and

Figure 3 is a perspective view thereof.

I claim:

The ornamental design for a combined handle
and standard for a sadiron or similar article,
substantially as shown.
